ABSTRACT

Individual, low volume metering pumps are provided for supplying moisture to each nozzle in a bank of adjacent nozzles directing moisture toward the inking train. The metering pumps are driven through commonly mounted eccentric cam rollers respectively engaging adjustable rocker arms for accurately varying the moisture output of each nozzle while variation of a master drive controls overall bank output. Selectively operable pistons are associated with individual output check valves for system priming or bubble clearance.

SPRAY DAMPENING SYSTEM WITH INDIVIDUAL METERING PUMPS FOR OFFSET PRESS

This invention relates to improved dampening apparatus for lithographic offset printing presses and more particularly to such apparatus which permits fine control for optimum dampening under highly varied conditions of press speed and ink requirements.

It is known that the practice of offset lithography printing requires sufficient but not excessive dampening of the printing member to allow ink transfer where desired and yet prevent ink from adhering to those portions of the member which are free of printing areas. Devices for supplying moisture to printing presses for this purpose are numerous and vary greatly in complexity and operation. Heretofore, however, the use of such devices has presented certain drawbacks which tend to adversely affect the speed, cost or quality of production. Among these drawbacks are: lack of precise control so that an improper quantity of moisture is supplied for the particular press speed; insufficient or excess moisture in certain positions along the printing plate where printing density varies from neighboring areas; contamination of the moisture supply due to paper lint or other foreign material entering open moisture reservoirs or exposed dampening rolls; contamination of the moisture supply due to improper ink movement; and improper composition of dampening mixture due to the evaporation of volatile components from exposed supply sources.

The principal objects of the present invention are: to provide dampening apparatus for offset printing presses which overcomes the above-noted disadvantages; to provide such apparatus which is relatively inexpensive to manufacture and easily adapted to the printing press; and to provide such apparatus which is highly reliable and requires a minimum amount of attention for operation or maintenance.

Other objects and advantages of this invention will become apparent from the following description taken in connection with the accompanying drawings wherein are set forth by way of illustration and example certain embodiments of this invention.

FIG. 1 (A and B) is a fragmentary side elevation illustrating dampening apparatus embodying this invention including a pump member and a spray member mounted on a rotary web press with portions broken away to show interior construction.

FIG. 2 is a fragmentary plan view illustrating the pump member of FIG. 1A with portions broken away further showing interior construction.

FIG. 3 is a fragmentary plan view illustrating the spray member of FIG. 1B with portions broken away showing interior construction.

FIG. 4 is a front elevational view of the spray member of FIG. 3.

FIG. 5 is a rear elevational view of the spray member of FIG. 3 with the back plate removed.

FIG. 6 is an end elevation of the spray member of FIG. 3.

FIG. 7 is a cross-sectional view through the spray member taken on the line 7-7, FIG. 3, particularly showing passageway construction for feeding air and liquid to the respective nozzles.

The reference numeral 1 generally indicates dampening apparatus embodying this invention. The apparatus 1 is illustrated in conjunction with rotary web printing press 2 (FIG. 1B) of a conventional type having an ink transfer train 3 including an ink fountain 4, hard metal rollers 5-9 and relatively soft (rubber) rollers 10-17. Through the ink transfer train 3, ink 18 in the fountain 4 is evenly distributed and transferred to the lithographic printing plate 19 on a plate roller 20. The ink 18 adheres to the plate 19 only at predetermined locations, and the image formed is transferred to a blanket cylinder 21. From the cylinder 21, the image is deposited upon the moving paper web 22 which is maintained in contact with the cylinder 21 by means of an impression cylinder 23. The press cylinders above described are driven directly or indirectly through a typical drive shaft 24 which synchronizes the printing operation with other parts of the printing press in a known manner.

Referring to this invention, the apparatus 1 includes a spray member 25 (FIG. 1B) mounted on the press 2 adjacent the ink transfer train 3 and a pump member 26 (FIG. 1A) mounted in spaced relation to the spray member 25 but connected thereto with multiple hoses, as described below.

The spray member 25 has an elongated body portion 27 (FIG. 3) mounted on the press 2 longitudinally adjacent the inking rollers 9, 8 and 16. The body portion 27 is secured at one end 28 by means of a clamp 29 engaged with a supporting rod 30 extending across and suitably anchored to the side walls of the printing press 2. The end 28 has a threaded stud 31 projecting longitudinally therefrom and threadedly received in a knurled circular nut 32 which is removably nested within a slot 33 formed in the clamp 29. The manual rotation of the nut 32 urges the body portion 27 longitudinally of the stud 31 in either direction, depending upon the direction of nut rotation.

The other end 34 of the body portion 27 has a plurality of longitudinally projecting passageway connectors 35 and 36 which are received in a mounting block 37 secured to the supporting rod 30 by means of a clamp 38 similar to clamp 29 noted above. The block 37 has sockets 38' for receiving the passageway connectors 35 and 36 and guide pins 39 projecting from a back plate 41. The back plate 41 also supports the stud 31 and is secured to the rear surface of the body portion 27. The clamps 29 and 38 are spaced apart a distance sufficient to permit unplugging and reconnecting the passageway connectors 35 and 36 and guide pins 39 upon rotation of the nut 32 in opposite directions, whereupon the spray member 25 may be conveniently removed and replaced as desired. The stud 31 is laterally withdrawn, that is, toward the left as shown in FIG. 1B, from a slot 42 formed in the clamp 29 when removing the spray member 25.

A plurality of spray nozzles 43 are secured in linear, laterally spaced relation on the spray member body portion 27 and are directed, in this example, toward the nip between the roller 17 and lowermost roller 9, FIG. 1B. The spray nozzles 43 are preferably of the fine spray type marketed by Spraying Systems Co. of Bellwood, Illinois, designated No. 2050. The nozzles 43 have threaded mounting portions received in threaded bores 44 extending into the body portion 27 and are characterized by a central passageway 45 directed axially therethrough and having a fine exit opening 46 (FIG. 7) at the exposed tip. The passageways 45 communicate rearwardly into chambers 47 which are fed through a passageway 48 drilled transversely into the body portion 27. The passageways 48 connect with elongated slots 49 (FIG. 5) milled longitudinally into the rear surface 50 of the body portion 27 whereby upon mounting the back plate 41, for example, by means of suitable screws 51, the respective slots 49 form individual passageways. The slots 49 connect with transverse bores 52 which in turn connect with longitudinal bores 53, the latter receiving the passageway connectors 35 thereinto.

The threaded bore 44 is surrounded by a tubular recess 54 which communicates at the outer end thereof with nozzle passageways 55 and at the inner end thereof with an elongated bore 56 extending into the body portion 27 along the bank of nozzles 43.

As discussed further below, the slots and passageways 49, 48 and 45 carry dampening liquid in measured quantities to the respective nozzles 43 and the bore 56, recess 54 and nozzle passageways 55 carry compressed air for atomizing and propelling the liquid from the nozzle. The block 37 (FIG. 3) serves both as a connector-mount for the spray member 25 and an anchor to receive liquid transmitting hoses 57 and a compressed air transmitting hose 58, the hoses leading from the pump member 26 now described.

The pump member 26 (FIGS. 1A and 2) comprises a frame 59 mounted, in this example, by means of a bracket 60 to a convenient location on the frame of the press 2 near the spray member 25. The frame 59 includes a manifold block or portion 61 into which the hoses 57 and 58 communicate.

In this example, an individual valve block 62 is provided for each of the nozzles 43. The blocks 62 include a pump recess 63 extending thereto from an exterior surface 64, the recess 63 here being formed by bores extending through the block. The blocks 62 are mounted by suitable screws 65 onto the manifold portion 61 with the recess 63 against an exterior surface 66 of the manifold portion 61. A plurality of bores 67 extend in laterally spaced relation through the manifold portion 61 and are respectively axially aligned with the recesses 63. Flexible diaphragm seals 68 have a front surface 69 and a rear surface 70 and are positioned between the respective recess 63 and the bores 67. The diaphragm seals 68 cover the respective recess 63 with the front surface 69 thereof and isolate the respective recesses from the manifold portion bores 67.

Plungers 71 are reciprocably received in the respective manifold portion bores 67 and bear at a forward, rounded end 72 against the respective diaphragm seal rear surface 70. Helical compression springs 73 surround the respective plungers 71 and bear against a collar 74, urging the diaphragm seal 68 into sealing engagement with the respective block exterior surface 64. The collar 74 slidably receives the end 72 of the respective plunger 71 therethrough, permitting reciprocal movement of the plunger against the diaphragm seal 68 without relieving the sealing pressure that the collar 74 exerts on the diaphragm seal. The other end of the helical spring 73 bears against an integral shoulder 75 formed on the respective plungers 71, thus urging the plunger resiliently away from the diaphragm seal 68.

The plungers 71 have projections 76 extending outwardly beyond the exterior surface 77 of the manifold portion 61 and received into sockets 78 located in the drive ends 79 of respective rocker arms 80. The rocker arms 80 each have an adjusting end 81 opposite from the drive end 79 and containing a socket 82 opening laterally in the same direction as the socket 78. A fulcrum rod 83 is anchored in side plates 84 and 85, which form part of the pump member frame 59, and extends along the manifold portion 61. The fulcrum rod 83 engages each of the respective rocker arms 80 at a point opposed to the rocker arms 80 and located between the drive and adjusting ends, as at 86, FIG. 1.

The sockets 82 receive the tips 87 of adjusting members 88, each having a handle 89 and a threaded extension 90 received in threaded bores 91 extending through the manifold portion 61. The tips 87 bear against the rocker arm adjusting ends 81, thereby adjustably limiting the length of the reciprocal stroke which can be taken by the respective plungers 71. A suitable spring ball detent 92 is resiliently urged against the handle 89 of the adjusting members and is selectively received in circumferentially spaced notches 93 for maintaining the adjusting member in a desired rotary position but permitting easy readjusting by manual rotation of the handle.

A drive shaft 94 is rotatably mounted on the pump member 26 in bearings supported on the mounting plates 84 and 85 and extends along the rocker arms 80. A plurality of eccentric cam rollers 95 are spaced along the drive shaft 94 and are respectively positioned adjacent the back side 96 of the rocker arm drive ends 79. The cam rollers 95 are rendered eccentric with the axis of the drive shaft 94, for example, one thirty-second inch, through mounting on a bearing 97 having an eccentric inner race or collar, whereby the rotation of the shaft 94 reciprocally drives the plungers 71 through the rocker arm drive ends 79 although the outer ring 98 of the cam rollers 95 may remain rotationally stationary. A variable speed electric motor 99 is mounted on a support plate 100 forming part of the pump member 26 and is operably connected through a right angle gear drive 101 to the shaft 94 for rotating shaft 94 at a desired speed. A suitable universal joint coupling 102 provides a physical connection between the motor assembly and the shaft 94.

Referring to the valve blocks 62, in this example, a flat headed pin 103 (FIG. 1A) is contained in the recess 63 bearing against the front surface 69 of the diaphragm seal. The body of the pin 103 is received axially within a helical com-

pression spring 104 urging the pin against the seal and also bearing against a screw plug 105. The screw plug 105 includes a head 106 sealed against the surface 107 of the respective valve block 62 by means of a suitable "O" ring 108. Thus, a pump chamber 109 is formed by the recess 63 between the screw plug and the diaphragm seal.

Lower and upper drilled passageways 110 and 111 (FIG. 1A) communicate into the chamber 109 and also respectively into an intake valve chamber 112 and an output valve chamber 113 formed in the respective lower and upper portions of the valve blocks 62. The intake valve chamber 112 has a valve disc 114 resiliently seated therein by means of a helical spring 115 compressed thereagainst with a threaded seal plug 116. The intake valve chamber 112 communicates through a bore 117 with a manifold passageway 118 formed in the manifold portion 61 (FIGS. 1A and 2). The manifold passageway 118 is branched along its length as at 119, thereby communicating with each bore 117 in the respective valve blocks 62. A seal is maintained between the blocks 62 and manifold portion 61 by means of suitable "O" rings 120 compressed against the manifold portion surface 66. The manifold passageway 118 is fed dampening liquid through a mouth 121 connected by suitable fittings 122 to a closed container 123 holding the liquid. A suitable plug 124 seals an access port into the manifold passageway 118.

The output valve chambers 113 have valve discs 125 resiliently seated therein by means of helical springs 126 bearing thereagainst through pressure exerted by threaded plugs 127 having central passageways therethrough. The passageways in the plugs 127 provide communication between the valve chambers 113 and respective passageways 128 in the manifold portion 61. The passageways 128 receive the ends 129 of the hoses 57, the hose ends being sealed therein through "O" rings 130 urged into sealing engagement with pressure exerted by a block 131 secured to the manifold portion 61 by screws 132.

The output valve chambers 113 have piston rods 133 received partially thereto and slidably sealed through "O" rings 134 maintained under compression with threaded collars 135. Helical compression springs 136 surround the piston rod 133 and normally urge same away from the valve disc 125. A transverse bar 137 bears against each of the piston rods 133 moving the bar 137 toward the valve block 62, as by an air cylinder 138, will result in discharging substantially the entire contents of the output valve chambers 113.

A motor control 139 (FIG. 1A) of a known type is adapted to vary the output speed of the motor 99. A commercially available sensor 140 is associated with the drive shaft 24 and is adapted to produce a signal proportional to the rotational speed of the drive shaft and, hence, the web printing speed of the press. The speed sensor 140 cooperates with the motor control 139 in a well known manner whereby the rotation of the motor 99 may be directly related to the rotational speed of the drive shaft 24. Preferably, the relationship between the drive shaft speed and motor speed will not be linearly proportional, since dampening requirements have been found to be proportionately higher at lower press speeds; however, when the shaft speed is zero, the motor should be off to prevent dripping of unused moisture.

Compressed air, for example at 5 p.s.i.g., is introduced through a hose 141 anchored to the manifold portion 61 by a fitting 142. The compressed air is then directed through a fitting 143 (FIG. 2) into the hose 58 which feeds the bore 56 through the block 37.

In operation, the dampening liquid, normally comprising a mixture of water and certain volatile additives such as isopropyl alcohol, is held in the container 123 which is closed against external contamination. The dampening liquid flows downwardly through the fittings 122 into the manifold passageway 118 and branches 119 from which it enters into the bores 117 feeding the intake valve chambers 112. The rotation of the motor 99 at a predetermined speed, in response to the rotation of the drive shaft 24, causes the drive shaft 94

to rotate whereupon the respective bearing outer rings 98 orbit eccentrically. The orbiting of the outer rings 98 periodically urges the drive ends 79 of the rocker arms 80 toward the respective plungers 71, the length of stroke being, in part, determined by the adjustment of the adjusting members 88. That is, the adjusting members 88 adjustably limit the distance the plunger springs 73 may urge the rocker arms 80 toward the rings 98.

The reciprocation of the plungers 71 is reflected in the similar movement of the diaphragm seals 68, which alternately increase and decrease the volume of the pump chambers 109, creating positive displacement pumping. The return stroke of the diaphragm seals 68 is aided by the springs 104 acting upon the diaphragm contacting pins 103. The volume increase in the chambers 109 causes a reduction in chamber pressure which draws dampening liquid into the bores 117, past the check valve discs 114, into the valve chambers 112 and upwardly into the chambers 109 through the passageways 110. The alternate decrease in chamber volume causes the valve discs 114 to close, raising the pressure within the chambers 109 and forcing the dampening liquid upwardly through the passageways 111 and into the output valve chambers 113. The continued sequence of diaphragm seal reciprocation forces the dampening liquid to open the output valve discs 125 whereupon the dampening liquid flows through the passageways 128 and into the respective hoses 57 individually feeding liquid in metered quantities to the spray nozzles 43. The quantity of liquid supplied to individual nozzles is controlled in relation to the other nozzles by the individual adjusting members 88, while the overall system liquid supply is controlled by the rotational speed of the motor 99 as determined by the rotational speed of the drive shaft 24.

Air in the hose 58 is distributed by the body portion bore 56 into the respective tubular recesses 54 (FIG. 7) where it is discharged through the respective spray nozzles 43 (FIG. 1B) in a known manner for atomizing and transporting the liquid in minute particles to the ink train for regulating the ink-water balance required for quality offset printing.

Thus, with the use of the above apparatus, there is no contamination or backfeed of the dampening fluid; the premature evaporation of volatile components is prevented, and precise control is provided over individual portions along the printing plate as well as overall quantity requirements dictated by press speed.

Due to the very small quantities of liquid being pumped, system priming or bubble clearance may constitute an important consideration in accurate pump operation. In the above-described apparatus both of these functions are conveniently and effectively accomplished by the periodic actuation of the piston rod 133 by the air cylinder 138 (FIG. 2). Bubbles forming or collecting within the system which could interfere with the pumping function tend to move to the highest point between the intake and output valves, which here constitutes the output valve chamber 113 (FIG. 1A). Depressing the piston rod 133 empties the output valve chamber 133 whereby such bubbles which have collected are forced downstream into the respective hoses 57 where they are harmlessly eliminated during normal system operation. It has been found sufficient to provide an actuating control (not shown) in conjunction with the normal printing press operating controls (not shown) which causes the air cylinder 138 to be actuated for a single reciprocation each time the press begins a web printing run.

It is to be understood that although one form of this invention has been illustrated and described it is not to be limited specifically thereto.

What I claim and desire to secure by Letters Patent is:

1. In combination with a printing press having drive means, an inking train, and an offset plate on a plate cylinder which in turn engages a blanket cylinder for transferring an ink image thereto, dampening apparatus comprising:

a. a spray member operably directed toward said plate cylinder and having a plurality of liquid atomizing spray

5

nozzles positioned on said press in laterally spaced relation, said spray nozzles respectively having unvalved liquid exit openings, gas directing means adjacent said respective exit openings for atomizing liquid flow out of said exit openings, individual dampening liquid output conduit means connected at one end thereof to said respective exit openings,

- b. a pump member having a plurality of individual metering pumps respectively including an input portion containing an input valve, an output portion containing an output valve and a pump pathway extending between said valves,
  - c. said output conduit means being connected at the other end thereof to said respective metering pump output portions,
  - d. an output valve chamber in said pump pathway upstream from said output valve,
  - e. reciprocating pump means communicating with said pump pathway between said valves and alternately increasing and decreasing the volume in said pump pathway,
  - f. flushing means communicating with said pump pathway and selectively operable in addition to and substantially independently of said pump means to discharge contents of said output valve chamber past said output valve and into said respective output conduit means,
  - g. a source of dampening liquid including input conduit means connected to said respective pump input portions,
  - h. drive means associated with said press drive means for driving said pump means, and
  - i. means associated with said pump means for individually adjusting the volume variation in said respective pump pathways,
  - j. said dampening apparatus being substantially isolated from atmospheric exposure between said dampening liquid source and said exit openings.
2. The combination as set forth in claim 1 wherein:
- a. said flushing means includes a piston receivable into said output valve chamber.
3. The combination as set forth in claim 1 wherein:
- a. said output valve chamber is elevated above said input valve.
4. The dampening apparatus as set forth in claim 1 wherein:
- a. said metering pumps each include a valve block secured to said manifold portion,
  - b. said valve blocks each having said pump pathway therein, and said reciprocating pump means includes a recess in said respective valve blocks forming a pump chamber.
5. The apparatus as set forth in claim 4 wherein:
- a. said input conduit means includes a manifold portion having a plurality of bores extending therethrough and respectively aligned with said block recesses,
  - b. said reciprocating pump means includes a flexible diaphragm seal having front and rear surfaces and positioned between each of said respective recesses and manifold portion bores, said diaphragm seal covering said recesses with said front surfaces and isolating said recesses from said manifold portion,
  - c. a plurality of plungers reciprocally received in said respective manifold portion bores and bearing at one end respectively thereof against said diaphragm seal rear surfaces,
  - d. said individually adjusting means includes means for adjustably reciprocating said plungers against said diaphragm seal rear surface.
6. The combination as set forth in claim 1, wherein:
- a. a portion of said inking train is operably positioned between said spray nozzles and said plate cylinder.
7. The dampening apparatus as set forth in claim 1 wherein:
- a. said metering pumps each include a reciprocally mounted plunger for displacing said dampening liquid, and
  - b. a rocker arm operably engaging said plunger, said rocker arm being adjustably mounted for selectively limiting the stroke length of said plunger.
8. The dampening apparatus as set forth in claim 1 wherein:

- a. said spray member includes a body portion, and
  - b. said individual dampening liquid conduit means includes elongated slots extending in said spray member body portion.
9. The dampening apparatus as set forth in claim 1 wherein:
- a. said metering pumps each include a reciprocally mounted plunger for displacing said dampening liquid,
  - b. a rocker arm for each of said plungers and having a drive end and an adjusting end, a fulcrum rod mounted on said pump member and engaging said rocker arms between said drive and adjusting ends, said plungers bearing at one end thereof against said respective rocker arm drive ends,
  - c. a drive shaft rotatably mounted on said pump member and extending along said rocker arms, a plurality of ec-

15

- centric cam rollers spaced along said drive shaft and respectively positioned adjacent said rocker arm drive ends, said cam rollers being eccentrically offset sufficiently to reciprocably drive said plungers through said rocker arm drive ends upon rotation of said drive shaft,
- d. a plurality of adjusting members each having a threaded extension, said adjusting member extensions respectively being threadedly received in said pump member manifold portion and having ends adjustably bearing against said rocker arm adjusting ends for selectively limiting the stroke of said plungers toward said cam rollers, and
- e. said pump drive means engages said drive shaft for rotating said drive shaft.
